MULTIPLE CONNECTOR BLOCK

Harry John Dell, Camp Hill, and Charles Robert Stoyer III, Enola, Pa., assignors to AMP Incorporated, Harrisburg, Pa.

Filed Mar. 10, 1965, Ser. No. 84,180

Term of patent 14 years

(Cl. D26—1)

FIGURE 1 is a perspective view of a multiple connector block, showing our new design with the parts in assembled condition;

FIGURE 2 is an exploded perspective view;

FIGURE 3 is a side elevational view of each part of the block;

FIGURE 4 is a rear elevational view of each part of the block looking at the left in FIGURE 3; and

FIGURE 5 is a front elevational view of each part of the block looking at the right in FIGURE 3.

We claim:

The ornamental design for a multiple connector block, as shown.
